UNITED STATES PATENT OFFICE.

CHARLES B. McVAY, JR., OF WASHINGTON, DISTRICT OF COLUMBIA, ASSIGNOR TO THE GOVERNMENT OF THE UNITED STATES.

TORPEDO.

Application filed April 6, 1923. Serial No. 330,383.

To all whom it may concern:

Be it known that I, CHARLES B. McVAY, Jr., a citizen of the United States, residing at Washington, District of Columbia, have invented new and useful Improvements in Torpedoes, of which the following is a specification.

This invention relates to improvements in torpedoes and more particularly to means adapted to aid in controlling the depth to which the torpedo may go on initial launching.

One of the objects of the present invention is to provide a torpedo with an attachment known in the Navy as a "drogue" adapted to control to a certain extent the depth of initial dive of the torpedo when launched.

A further object is to provide a device of the above general character having relatively few parts which may be inexpensively manufactured, assembled and installed.

A further object is to provide a device of the above character particularly adapted for use in connection with torpedoes launched from aircraft where owing to the inability of keeping the aircraft on an absolutely even keel at the moment of launch there is a tendency for the torpedo to have a downward inclination at the moment of launching which causes the same to dive to an abnormal depth and in shallow water stick on the bottom before the normal regulating mechanisms can go into operation.

A further object is to provide a device of the above general character which after completing its service will automatically become detached from the torpedo thereby allowing the torpedo to continue its run without retardation due to the presence of the drogue.

With these objects in mind, attention is directed to the accompanying sheet of drawings showing in elevation the forward end of a torpedo with the drogue attached thereto.

Referring now to this drawing in detail, 1 indicates the forward end of a torpedo and as illustrated shows what is known as the practice or dummy head provided at its forward end with a ring 2 which is used as an attaching means for recovering the torpedo after its practice run.

For the purpose of illustration the drogue is shown as attached to this ring 2 although

it is of course to be understood that any desired form of attaching means may be substituted for this ring which occupies the place usually devoted to the fixing mechanism.

The drogue comprises a member 3 preferably cylindrical in shape and of light or buoyant material such as wood or cork provided with an attaching ring 4 to which a line 5 several feet in length is secured at one end. The opposite end of this line is secured to what would be broadly termed detaching means 6 the opposite end of which is connected to the ring 2 in any desired manner.

As herein shown and described, this detaching means comprises simply a link, cord or wire of predetermined tensile strength, that is, a material adapted to break or release at a stress of say 1300 or 1500 lbs. Obviously any desired form of detaching means may be substituted if desired but this form has been found in practice to work satisfactorily and being of such very simple, practical and inexpensive construction it is for these reasons initially desirable.

In operation the torpedo is secured to the under side of an aircraft or plane by a plurality of straps which are simultaneously released when the plane swoops down relatively close to a water level and while flying towards the target. At the moment of release the driving mechanism of the torpedo is started and the same drops into the water the torpedo will continue its run.

As above stated, however, it is difficult to control the relative position and level of the plane and the torpedo may be released while the plane is downwardly inclined. This would have a tendency to cause the torpedo to dive to an abnormal depth and possibly do serious harm before equilibrium could be restored, that is, the engine might be stopped or the torpedo might stick in the bottom.

With the provisions of the drogue, however, a resistance or counterpull is exerted on the nose of the torpedo at the moment of launching; that is, to and including submergence, tending to keep or pull the head-end upwards and prevent an abnormal dive thus positively insuring a more rapid establishment of equilibrium and the continuance of the run of the torpedo at the desired predetermined depth. After this has been ac-

complished the pull exerted by the drogue will cause an actuation of the detaching means of the character herein shown and release the buoyant member thereby eliminating any retardation of the speed of the torpedo by the action of the float 3.

If a hydrostatic or time controlled device on the detaching means is used with the drogue these may take effect either at a pre-determined depth or at a predetermined time interval after launching as may be desired.

It will thus be seen that the present invention contemplates a simple, practical, reliable and efficient attachment for torpedoes particularly adapted to accomplish among others all of the objects and advantages herein set forth.

What I claim is:—

1. In combination with a torpedo, a float member, a connecting member interposed between the forward part of the torpedo and said member and means for detaching said float member from the torpedo immediately after complete submergence, thereby to prevent an abnormal dive.
2. In combination with a torpedo, a member, a connecting member interposed between the forward part of the torpedo and the member and means for detaching the member from the torpedo after the torpedo has been launched, said detaching means comprising a member of predetermined tensile strength adapted to break on a certain pull.
3. In combination with a torpedo, a buoyant member, a line connecting said buoyant member with the forward part of the torpedo, and a link in said line adapted to break on predetermined pull thereby to release the buoyant member from the torpedo.
4. In combination with a torpedo, a resist-

ance member, a line connecting said resistance member with the forward part of the torpedo, and means in said line adapted to automatically detach said resistance member from the torpedo immediately after submergence whereby to pull the head of the torpedo upwardly and to avoid an abnormal dive.

5. In combination with a torpedo, a detachable drogue connected with the forward end thereof adapted to prevent an abnormal initial dive.

6. In combination with a torpedo, a buoyant member and a flexible connection between said member and the forward part of the torpedo adapted to prevent an abnormal initial dive of the torpedo.

7. In combination with a torpedo, a buoyant member, a flexible connection between said member and the forward part of the torpedo adapted to prevent an abnormal initial dive of the torpedo and means included in said flexible connection adapted to automatically release said member immediately after submergence of the torpedo and after the head of the torpedo has been pulled upwardly thus establishing equilibrium.

8. In combination with a torpedo, a buoyant member, a flexible connection between said member and the forward part of the torpedo adapted to prevent an abnormal initial dive of the torpedo and means in said flexible connection adapted to automatically release said member after the launching of the torpedo and when equilibrium has been established, said means comprising a link in said flexible connection adapted to break on predetermined pull.

Signed at Washington, District of Columbia, this 26th day of March, 1923.

CHAS. B. McVAY, JR.
